Inventor
John Roche

By W. H. Williamson

UNITED STATES PATENT OFFICE.

JOHN ROCHE, OF HOBOKEN, NEW JERSEY.

DIMMING HEADLIGHTS FOR AUTOMOBILES.

Application filed March 3, 1928. Serial No. 258,710.

My invention relates to a new and useful improvement in dimming head lights for automobiles, being a continuation in part of my former application for patent, Serial No. 238,481, dated December 8, 1927, and has for its object to provide a simple and effective device for dimming the light rays from an electric lamp so as to avoid the glare heretofore incident to the head lights of motor vehicles and to increase and decrease this modifying of the light and to put the same under the control of the driver whereby he may not only increase or decrease the light projected upon the road, but may utilize the light as a signal under a given code to warn the oncoming traffic of his intention to turn in one direction or another.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:—

30 Fig. 1, is a view of a portion of an automobile head light showing my present improvements applied thereto.

Fig. 2, is a rear view of Fig. 1, the casing and reflector being sufficiently broken away 35 to show the operating solenoid and other parts.

Fig. 3, is a rear view of the modifying bulb or electric lamp showing a portion of said bulb and showing the light modifying substance applied to portions of said bulb.

40 Fig. 4, is a view similar to Fig. 2 showing a slight modification of this invention in which mechanically operating means is substituted for the solenoid.

45 Fig. 5, is a broken away sectional view of Fig. 4.

In carrying out my invention as herein embodied, 10 represents the bulb having its front half coated with a light modifying substance, the rear of said bulb being also coated but in bands as indicated at 11 so as to leave alternate spaces 12 clear for the unobstructed passage of the light rays and around the rear portion of this bulb is fitted a shield 13, 55 said shield being so slotted as to either cover

these clear spaces in the bulb or to open the same by said shield by it being rotated upon its axis. This rotation is accomplished by the armature 14 of the solenoid 15, the latter being attached to the arm 16 carried by the shield; said shield being fitted to revolve upon the socket 17 in which the lamp is removably secured in the usual manner.

18 represents the wires leading to and from the solenoid, said wires being connected with any suitable switch (not shown) upon the instrument board of the vehicle, any suitable battery being included in the circuit, so that the solenoid may be energized or deenergized to rotate the shield to open the clear spaces in the rear portion of the bulb. The deenergizing of the solenoid will permit the closing of said spaces by the downward movement of the armature 14 through the action of gravity as will be readily understood.

In the slight modification shown in Figs. 4 and 5 the solenoid and its armature are dispensed with and a bell crank lever 25 is substituted therefor, one arm of said lever being connected by the wire 26 to the arm 16, while the other arm of the lever 25 has attached thereto a coupling rod 27 with which the rod 28 is coupled, the latter being intended to terminate upon the instrument board of the automobile, thereby giving the driver control over the rotation of the shield 13 by pulling upon the rod 28 and when this rod is released, the spring 29 will rotate the shield 13 in the opposite direction.

19 represents the casing of a motor vehicle head light in which is mounted the reflector 20 and this reflector has a super-imposed layer 21 applied to its reflecting surface of a translucent gum-like coating through which when 95 the rays of light pass to the reflector and are returned therefrom, said rays are modified to prevent the undue glare which is incident to the reflection of light from an electric lamp, thus modifying these rays to prevent an intense concentrated glare in front of the head light.

The bulb 10 being mounted at the center of the reflector and having its surface coated as before described, will further modify the light emanating therefrom and passing to the reflector, and when the shield is closed over the transparent portions of the bulb, this modified light will give sufficient illumination of the road bed to permit the safe driv-

ing of the automobile under ordinary condition, but when further illumination is desired, it is only necessary to rotate the shield as before described to uncover the transparent portions of the bulb when the amount of illumination projected to the road bed will be increased, but under the modifying effects of the coating upon the reflector, this illumination will still be so modified as to prevent glare.

Of course I do not wish to be limited to the exact details of construction as herein shown, as these may be varied within the limits of the appended claims without departing from the spirit of my invention.

Having thus fully described my invention, what I claim as new and useful is: —

1. In a motor vehicle head light; a reflector; an electric lamp mounted at the center of said reflector, the bulb of said lamp being partially coated with a light modifying substance; a shield for covering and uncovering the transparent portions of said bulb; an armature adapted to revolve said shield upon

its axis; and a solenoid for operating said armature.

2. In combination with a motor vehicle head light; a reflector; an electric lamp, the bulb of said lamp being mounted within said reflector, and also being partly coated with a light modifying substance, certain portions of said bulb being left transparent; a rotatable shield for covering and uncovering the transparent portions of said bulb; and means for revolving said shield upon its axis.

3. An automobile head light comprising a reflector; an electric lamp mounted within said reflector, a portion of said lamp being translucent and portions thereof being transparent; a shield having cut-away portions for opening and closing the transparent sections of the lamp; and means for revolving said shield, said means being under the control of the driver.

In testimony whereof, I have hereunto affixed my signature.

JOHN ROCHE.
